(57) **CLAIM**

The ornamental design for a front panel for vending machine, as shown and described.

DESCRIPTION

FIG. 1 provides a front isometric view of a front panel for vending machine provided by the present invention;

FIG. 2 provides a front elevational view of the present invention;

FIG. 3 depicts a back elevational view of the present invention;

FIG. 4 depicts a left side elevational view of the present invention;

FIG. 5 depicts a right side elevational view of the present invention;

FIG. 6 depicts a top planar view of the present invention; and,

FIG. 7 depicts a bottom planar view of the present invention. The broken lines in the drawings depict environmental structure, which forms no part of the claimed design.
